UNITED STATES PATENT OFFICE

149,427

DESIGN FOR A FLUORESCENT LIGHTING FIXTURE

Stanley E. Lindahl, Los Angeles, Calif.

Application March 4, 1947, Serial No. 137,338

Term of patent 7 years

(CL. D48—23)

To all whom it may concern:

Be it known that I, Stanley E. Lindahl, of Los Angeles, State of California, have invented a new, original, and ornamental Design for a Fluorescent Lighting Fixture, of which the following is a specification reference being had to the accompanying drawing, forming a part thereof.

In the drawing, the figure is a perspective of a fluorescent lighting fixture showing my new design. The panel of the end not shown is similar in appearance to the end shown.

I claim:

The ornamental design for a fluorescent lighting fixture, as shown and described.

STANLEY E. LINDAHL.
